REFRIGERATOR CAR DOOR

John F. O'Connor, Chicago, Ill., assignor to W. H. Miner, Inc., Chicago, Ill., a Corporation of Delaware

Application October 8, 1931. Serial No. 567,609

7 Claims. (Cl. 20—23)

This invention relates to improvements in refrigerator car doors.

One object of the invention is to provide a door construction for refrigerator cars comprising a single sliding door member for closing the door opening of the car, wherein simple and efficient means is provided for forcing the door tightly into the door opening and also disengaging the door from said opening, including a single rotary operating member mounted on the door and cooperating with bearing means slideable on tracks mounted above and below the door opening, the operating means also serving to support the door slideably on the car.

Another object of the invention is to provide in connection with a door operating mechanism of the character specified in the preceding paragraph means for at all times maintaining the door parallel to the wall of the car.

A more specific object of the invention is to provide in a refrigerator car a single sliding door for closing the door opening of the car, wherein the sliding door is carried by a vertically disposed rotary operating member having crank arms at the top and bottom ends thereof having the crank pin members thereof journaled in brackets slideable on guide rails or tracks disposed above and below the door opening, and wherein means is also provided for holding the door parallel to the car wall, the said means being in the form of a U-shaped guide link swiveled to the door and having the free ends of the arms thereof guided by one of said tracks or rails.

In the drawings, forming a part of this specification, Figure 1 is an elevational view of the side wall of a refrigerator car, illustrating my improvements in connection therewith. Figure 2 is a vertical sectional view, on an enlarged scale, corresponding substantially to the line 2—2 of Figure 1, said view being broken in order to accommodate the same to the sheet of the drawing. Figure 3 is a vertical sectional view, also on an enlarged scale, showing the upper portion of the door and corresponding substantially to the line 3—3 of Figure 1. Figure 4 is a vertical sectional view, corresponding substantially to the line 4—4 of Figure 2. And Figure 5 is a horizontal sectional view, corresponding substantially to the line 5—5 of Figure 1.

In said drawings, 10 indicates the side wall of the car, which side wall is provided with the usual door opening 11, closed by a single door 12.

In carrying out my invention, I provide broadly top and bottom tracks or rails A and B; a ro-

tary supporting and operating crank bar C journaled on the door in brackets D—D—D; upper and lower guide and journal brackets E and F; an actuating lever G; a U-shaped guide link H; and a pair of journal brackets K—K for the guide link.

The guide track A, which is disposed above the door opening, extends a sufficient distance to the right of the door opening to accommodate the door 12 for sliding movement so as to entirely clear the door opening 11. The track A also extends slightly beyond the left-hand end wall of the door opening, as clearly shown in Figure 1.

The lower guide rail or track B extends to the right of the door opening a distance less than the rail or track A. As shown in Figure 1, the track or rail B extends such a distance to the left as to have the end disposed beyond the vertical center of the door opening. Both rails A and B are of the same design, each having a plate like section 13, which is bolted to the side wall of the car, and a horizontally extending portion 14 terminating in a right angular section 15, which section forms the guide rail proper. As shown in Figures 1 and 2, the rail sections 15—15 of the two tracks project toward each other, that is, the rail of the upper track projects downwardly, while the rail of the lower track projects upwardly.

The operating member C comprises a vertically disposed rotary bar of substantially cylindrical cross-section having crank arms 16—16 at the top and bottom ends thereof. The bar is rotatably supported on the door 12 by the three brackets D—D—D. Each bracket is preferably of two-part construction, comprising a section 17, which is flanged and is secured directly to the door, and an outer separable section 18, which is secured to the section 17. The two sections of each bracket D provide a cylindrical journal portion receiving the corresponding part of the rotary bar C. Adjacent to the upper bearing member D, the bar C is provided with collars 19—19 above and below said bearing in embracing relation thereto. These collars hold the bar against vertical displacement with respect to the door. Adjacent to the central and lowermost bearings D—D, the bar C is also provided with collars 19—19, which engage the bottom portions of said bearings respectively.

As will be evident, the four collars 19—19, which cooperate with the three bearing brackets D—D—D, support the door 12 on the bar C. The upper crank member 16 has a cylindrical bearing element or boss 20 at the outer end

thereof, which cooperates with the combined guide and journal bracket E as hereinafter pointed out. At the outer end of the lower crank arm 16 of the bar C, a downward extension or projection 21 is provided, which is vertically centrally slotted, as indicated at 22. A guide roller 23 is disposed within the slot 22 and is journaled on a bearing pin 24 extending transversely through the member 21 at right angles to the slot 22. The bearing pin 24 is journaled in supporting sleeves 25—25, which are fixed within the member 21. As most clearly shown in Figure 2, the outer ends of the sleeves 25—25 and the opposite ends of the pin 24 are rounded for a purpose hereinafter pointed out.

The guide brackets E and F are respectively slidable on the tracks or rails A and B. The bracket E, which cooperates with the upper guide rail A, comprises a cuplike portion 26 having a cylindrical bearing seat 27 in which the member 20 of the upper crank arm 16 is journaled. The upper portion of the bracket E is slotted, as indicated at 127, to receive the rail 15 of the upper track A. As will be evident, the bracket E is thus slideable lengthwise of the rail 15 of the track A, while the crank arm 16 is swingable about the portion 20 thereof, which is journaled in the bracket E.

The bracket F comprises an upper socketlike portion 28 and a bottom extension 29. The extension 29 is slotted, as indicated at 30, to accommodate the rail 15 of the track B. The slot 30 opens through the bottom of the socket of the bracket F, thereby exposing the upper edge of the rail 15. As most clearly shown in Figures 2 and 4, the bottom portion of the wall of the socket of the bracket F is substantially spherical, and the side walls of said socket are lined with a bushing member 31, the inner surface of which forms a continuation of the spherical bottom surface of the socket. The socket is of circular, horizontal cross-section at all points and forms swiveling bearing means for the lower crank member 16 of the actuating bar C. The roller 23 is of such a diameter and the bearing pin 24 is of such a length that the periphery of the roller and the opposite ends of the bearing pin have bearing relation with the walls of the socket of the bracket F to provide for the swiveling movement of the crank arm 16 at the lower end of the bar C. The roller 23 normally rides on the rail 15 of the track B, as clearly shown in Figures 2 and 4, thereby supporting the bar C and through the latter the door 12 for sliding movement lengthwise of the car.

The guide link H is in the form of a U-shaped member having a horizontal section 32 and upwardly extending end arms 33—33. Adjacent to the upwardly extending arms 33—33, the horizontal section is provided with inward extensions 34—34 terminating in bearing portions 35—35 parallel to the horizontal section and journaled in the bearing brackets K—K, which are secured to the door 12 adjacent to the opposite side edges thereof. At the upper end, each arm 33 is provided with a right angular section 36 terminating in a yoke-like portion 37 having spaced side walls between which a grooved guide roller 38 is disposed. The roller 38 is journaled on a bearing pin 39 extending through the side walls of the member 37, as clearly shown in Figure 3. The link H is thus guided by the track A and restricted to longitudinal movement thereof but may swing outwardly on said track. Inasmuch as the horizontal section of the U-shaped guide link H is journaled at

opposite side edges of the door 12, the latter will at all times be held in parallel position with respect to the car wall, regardless of inward and outward displacement of the door with respect to the car. The guide link H thus serves the purpose of preventing accidental rotation of the door 12 about the axis of the operating bar C.

The actuating lever G is provided with an outwardly offset handle section 40 at the outer end thereof and has a horizontally disposed journal portion 41 at the inner end, which extends through the flattened portion 42 of the bar C. The lever G is fixed by means of a washer 43 of disclike form, which is held in position by the outer end of the bearing section 41 of the lever G being upset, as indicated at 44. As clearly shown in Figure 5, the door is cut away, as indicated at 45, to provide a seat to accommodate the enlarged section formed by the connection between the bar C and the operating handle lever G. In actuating the door to force the same either inwardly or outwardly of the opening 11, the operating bar is rotated through an angle of 180° by means of the handle lever G. In order to permit the 180° movement, the handle, when swung from one side of the bar C to the other, is rotated about the horizontal bearing thereof so that movement of the handle will not be interfered with by engagement with the outer surface of the door. The operating handle G is latched by the usual locking member 46 and sealed in the usual manner.

In opening the door 12, the handle G is unlatched and swung outwardly and toward the right, as viewed in Figure 1, thereby rotating the actuating bar C and swinging the same to the dotted line position shown in Figure 2. The door will thus be swung outwardly to the dotted line position shown in said figure, entirely clear of the side wall of the car. During this outward movement of the door 12, the guide link H holds the same in substantial parallelism to the side wall of the car, the necessary swinging movement being permitted by rocking of the rollers 38—38 at the upper ends of the arms 33—33 of the link H on the rail 15 of the upper guide track A and swiveling movement of the bearing portions 35—35 in the journal brackets K—K. The door is then slid to the right, as viewed in Figure 1, being supported on the lower track 15 by means of the roller 23 which rides on this track. The upper end of the actuating bar C is guided on the track A during this movement. As will be evident, when the door is in the fully opened position shown in dotted lines in Figure 2, the guide roller 23 will be in alignment with the rail 15 of the track B.

In closing the door, the operation is the reverse of that just described, the door being slid to the dotted line position shown in Figure 2 immediately in front of the door opening 11. With the door in alignment with the door opening, the operating bar C is rotated by the operating lever G in a direction reverse to that hereinbefore described, thereby moving the door inwardly to the full line position shown in Figure 2. After being forced tightly into the door opening, the operating lever G is locked and sealed in the usual manner.

I have herein shown and described what I now consider the preferred manner of carrying out my invention, but the same is merely illustrative and I contemplate all changes and modifications that come within the scope of the claims appended hereto.

I claim:

1. In door construction for refrigerator cars having a wall member provided with a door opening, the combination with a single door adapted to close said opening; of guide tracks on said wall member above and below said door opening; a bracket slidably guided on each track; a vertically disposed operating bar journaled on said door; crank arms at the top and bottom ends of said bar; means at the outer end of the lower crank arm journaled in the bracket of the lower guide track, said means including a roller journaled on the outer end of said arm having rolling engagement with said lower guide track; and a cylindrical crank pin member at the outer end of the upper crank arm journaled in the bracket of the upper guide track. 80
2. In door construction for refrigerator cars having a wall member provided with a door opening, the combination with a single door adapted to close said opening; of guide tracks on said wall member above and below said door opening; a bracket slideably guided on each track; a vertically disposed operating bar journaled on said door; crank arms at the top and bottom ends of said bar; means at the outer end of the lower crank arm journaled in the bracket of the lower guide track, said means including a roller on said arm rotatable about a horizontal axis and engaging said lower guide track; and a cylindrical crank pin member at the outer end of the upper crank arm journaled in the bracket of the upper guide track. 85
3. In door construction for refrigerator cars having a wall member provided with a door opening, the combination with a single door adapted to close said opening; of guide tracks on said member above and below said door opening; a vertically disposed operating bar journaled on the door, said bar having crank arms at the top and bottom ends thereof; a bracket slideably guided on said upper track; a bearing projection at the outer end of said top crank arm journaled in said bracket; a second bracket slideably guided on said lower track, said second named bracket having a socket portion provided with an opening in the bottom thereof exposing said lower track; and a supporting roller on said lower crank arm swiveled in said socket and riding on said lower track. 90
4. In door construction for refrigerator cars having a wall member provided with a door opening, the combination with a single door adapted to close said opening; of guide tracks on said member above and below said door opening; a vertically disposed operating bar journaled on the door, said bar having crank arms at the top and bottom ends thereof; a bracket slideably guided on said upper track; a bearing projection at the outer end of said top crank arm journaled in said bracket; a second bracket having a bearing socket therein, said bracket being slotted to slidably engage said lower track; a projection at the outer end of said lower crank arm; a roller on said projection; and a bearing pin for said roller, said pin being horizontally disposed and extending through said projection, the opposite ends of said pin and the periphery of said roller having bearing engagement with the walls of said socket for swiveling said lower crank arm in said bracket. 95
5. In door construction for refrigerator cars having a wall member provided with a door opening, the combination with a single door adapted to close said opening; of guide tracks on said member above and below said door opening; a vertically disposed operating bar journaled on the door, said bar having crank arms at the top and bottom ends thereof; a bracket slideably guided on said upper track; a bearing projection at the outer end of said top crank arm journaled in said bracket; a second bracket having a bearing socket therein, said bracket being slotted to slidably receive the lower track and said slot opening through the bottom of the socket to expose said track; and a roller on the outer end of said lower crank arm, said roller being supported by a horizontally disposed bearing pin fixed to said crank arm, said roller riding on the lower track, and the outer ends of said bearing pin and the periphery of said roller cooperating with the walls of said socket to swivel said lower crank arm to said bracket, said socket also forming a reservoir for lubricant. 100
6. In door construction for refrigerator cars having a wall member provided with a door opening, the combination with a door for closing said opening; of a vertically disposed rotary operating bar having crank means at the upper and lower ends thereof cooperating with means mounted on the wall member of the car for forcing said door inwardly and outwardly; and an actuating lever connected to said bar for rotating the same, said lever having a journaled connection with the bar to provide for rotation of said actuating lever about a horizontal axis parallel to the longitudinal axis of the lever. 110
7. In door construction for refrigerator cars having a wall member provided with a door opening, the combination with a door for closing said opening; of an operating bar rotatable about a vertical axis having crank means at the upper and lower ends thereof cooperating with means mounted on the wall member of the car for forcing said door inwardly and outwardly; and a horizontally disposed operating lever for rotating said bar about its vertical axis, said lever being journaled on said bar for rotation about a horizontal axis substantially parallel to the longitudinal axis of the lever. 115
8. In door construction for refrigerator cars having a wall member provided with a door opening, the combination with a single door adapted to close said opening; of guide tracks on said member above and below said door opening; a vertically disposed operating bar journaled on the door, said bar having crank arms at the top and bottom ends thereof; a bracket slideably guided on said upper track; a bearing projection at the outer end of said top crank arm journaled in said bracket; a second bracket having a bearing socket therein, said bracket being slotted to slidably engage said lower track; a projection at the outer end of said lower crank arm; a roller on said projection; and a bearing pin for said roller, said pin being horizontally disposed and extending through said projection, the opposite ends of said pin and the periphery of said roller having bearing engagement with the walls of said socket for swiveling said lower crank arm in said bracket. 120
9. In door construction for refrigerator cars having a wall member provided with a door opening, the combination with a single door adapted to close said opening; of guide tracks on said member above and below said door opening; a vertically disposed operating bar journaled on the door, said bar having crank arms at the top and bottom ends thereof; a bracket slideably guided on said upper track; a bearing projection at the outer end of said top crank arm journaled in said bracket; a second bracket having a bearing socket therein, said bracket being slotted to slidably receive the lower track and said slot opening through the bottom of the socket to expose said track; and a roller on the outer end of said lower crank arm, said roller being supported by a horizontally disposed bearing pin fixed to said crank arm, said roller riding on the lower track, and the outer ends of said bearing pin and the periphery of said roller cooperating with the walls of said socket to swivel said lower crank arm to said bracket, said socket also forming a reservoir for lubricant. 125
10. In door construction for refrigerator cars having a wall member provided with a door opening, the combination with a single door adapted to close said opening; of guide tracks on said member above and below said door opening; a vertically disposed operating bar journaled on the door, said bar having crank arms at the top and bottom ends thereof; a bracket slideably guided on said upper track; a bearing projection at the outer end of said top crank arm journaled in said bracket; a second bracket having a bearing socket therein, said bracket being slotted to slidably receive the lower track and said slot opening through the bottom of the socket to expose said track; and a roller on the outer end of said lower crank arm, said roller being supported by a horizontally disposed bearing pin fixed to said crank arm, said roller riding on the lower track, and the outer ends of said bearing pin and the periphery of said roller cooperating with the walls of said socket to swivel said lower crank arm to said bracket, said socket also forming a reservoir for lubricant. 130
